INVENTOR:

W. B. Weeden

UNITED STATES PATENT OFFICE.

WILLIAM B. WEEDEN, OF PROVIDENCE, RHODE ISLAND.

DESIGN FOR WOVEN FABRIC.

Specification forming part of Design No. 7,852, dated November 10, 1874; application filed September 5, 1874.
[Term of Patent 3½ years.]

CASE B.

To all whom it may concern:

Be it known that I, WILLIAM B. WEEDEN, of the city and county of Providence, in the State of Rhode Island, have invented a new Design for Fancy Cassimere Fabrics; and I do hereby declare that the following specification, taken in connection with the drawings making a part of the same, is a full, clear, and exact description thereof.

Referring to the drawings, A A represent stripes, which run lengthwise of the fabric, and are apparently bounded at their edges by narrow stripes *a a*, which are produced by color-shading, the effect of which shading is to give to the boundary stripes *a a* the appearance of being raised above the surface of the portion of the fabric between them. The several stripes A, with their edge-stripes *a a*, al-

ternate with a crape-cord, b, and cross-bars c set upon a ground of plain weaving, and forming ornamental stripes B B. The fabric may be made in any preferred variety or combination of colors, for giving effect to the design above described, the characteristic feature of which is the combination of the apparently sunken stripes A A, bounded by the shaded-edge stripes *a a* with the peculiarly ornamental intermediate stripes B B.

What I claim as my invention is—

The design for cassimere fabrics as herein set forth, and represented in the drawings.

WILLIAM B. WEEDEN.
